UNITED STATES PATENT OFFICE.

VICTOR L. BUCHER AND JACK R. HAMMEL, OF DAYTON, OHIO.

DESIGN FOR AN ADVERTISING DISPLAY COUNTER.

Application filed January 11, 1929. Serial No. 29,573. Term of patent 14 years.

To all whom it may concern:

Be it known that we, VICTOR L. BUCHER and JACK R. HAMMEL, citizens of the United States, residing at Dayton, in the county of Montgomery and State of Ohio, have invented a new, original, and ornamental Design for Advertising Display Counters, of which the following is a full, clear, and exact specification, reference being had to the accompanying drawing, forming part thereof.

In the drawings:

Figure 1 is a top plan view,

Figure 2 is a rear elevation,

Figure 3 is a front elevation and

Figure 4 is a side view in perspective of an advertising display counter, showing our new design.

We claim:

The ornamental design for an advertising display counter, as shown.

In testimony whereof we hereto affix our signatures.

VICTOR L. BUCHER.
JACK R. HAMMEL.
